United States Patent

Des. 240,466
Patented July 6, 1976

240,466

CURLING IRON

Joseph A. Rinaldi, Oradell, N.J., assignor to
The Gillette Company, Boston, Mass.

Filed Dec. 16, 1974, Ser. No. 533,206

Term of patent 14 years

Int. Cl. D28—03

U.S. Cl. D86—10 E

*Fig. 4**Fig. 5**Fig. 6*FIG. 1 is a perspective view of a curling iron showing my new design, the cord depicted only partially for ease of illustration;

FIG. 2 is an end view in the direction of arrows II—II of FIG. 1;

FIG. 3 is an end view in the direction of arrows III—III of FIG. 1;

FIG. 4 is a top plan view thereof;

FIG. 5 is a bottom plan view thereof; and

FIG. 6 is a side elevational view thereof.

I claim:

The ornamental design for the curling iron, as shown and described.
